No. 650,311.

Patented May 22, 1900.

D. FRANK.

BEDSTEAD.

(Application filed Nov. 29, 1899.)

(No Model.)

UNITED STATES PATENT OFFICE.

DAVID FRANK, OF NEW YORK, N. Y., ASSIGNOR OF ONE-HALF TO JOHN TROUNSTINE, OF SAME PLACE.

BEDSTEAD.

SPECIFICATION forming part of Letters Patent No. 650,311, dated May 22, 1900.

Application filed November 29, 1899. Serial No. 738,651. (No model.)

To all whom it may concern:

Be it known that I, DAVID FRANK, a citizen of the United States, and a resident of New York, (Brooklyn,) in the county of Kings and 5 State of New York, have invented certain new and useful Improvements in Bedsteads, of which the following is a specification.

The invention relates to improvements in bedsteads, and pertains more particularly to 10 novel fastening means to be employed at the corners of the bedstead for connecting together the posts and side rails.

The object of my invention is to produce fastening devices which are entirely durable 15 and efficient and will prevent any looseness between the connected parts of the bedstead, the side rails and corner-posts being by my invention capable of firm and rigid connection with one another and at the same time 20 adapted to be separated in the proper manner without inconvenience.

My invention consists in the novel features and combinations of parts hereinafter described, and pointed out in the claims, and 25 the nature and objects of the invention will be fully understood from the detailed description hereinafter presented, reference being had to the accompanying drawings, in which—

Figure 1 is a side elevation of fastening devices embodying my invention, said figure also showing a portion of one bed-post and, by dotted lines, a portion of one side rail and of one of the transverse beams connected with the usual spring-frame. Fig. 2 is a vertical 35 section of same on the dotted line 22 of Fig. 1. Fig. 3 is a top view of same. Fig. 4 is a view corresponding with Fig. 1, but illustrating a slightly-modified outline of one of the fastening-plates, the form of plate presented in Fig. 4 being employed when it is not desired to use a spring-frame having the special 40 transverse beam indicated in Figs. 1, 2, and 3. Fig. 5 is a vertical section of same on the dotted line 55 of Fig. 4; and Fig. 6 is a detached side elevation of a portion of the fastening devices, taken from the outer side of same.

In the drawings, 10 denotes the usual bed-post, and 11 one of the usual side rails. To 45 the bed-post 10 is applied a fastening-plate 12, and to the side rail 11 is secured a fastening-plate 13, said fastening-plates 12 and 13 being of special construction and embracing the

novel features of the invention sought to be protected. The plate 12 will preferably be 55 cast upon the post 10 and may be in one integral piece, or the section 14 of said plate may be wrought metal and secured to the other portion of said plate by being at one edge cast into the same by means of a chill in a well-known manner. In the present description I shall consider the plate 12, including its section 14, as being in one integral cast piece and cast upon the bed-post 10. The plate 12 in its present form possesses the down- 60 wardly and outwardly inclined wedge-surfaces 15, which also incline laterally inward toward the post 10, said wedge-surfaces 15 terminating at their inner edges against the vertical section 14, which preferably is 70 centrally disposed with respect to said plate 12 and is formed with the two hooks 16, 16 to receive the laterally-projecting rigid pins 17, carried by the fastening-plate 13. The wedge-surfaces 15 possess the double inclination indicated above—that is, they incline downwardly and outwardly from the post 10 and also inwardly and laterally toward one another and toward the post 10—and I prefer to form both of the surfaces 15 upon the plate 12, 80 although but one of the said surfaces can be used at one time, since thereby the post 10, carrying the plate 12, is adapted to receive either the right-hand fastening-plate 13 or the left-hand fastening-plate 13, the plate 12 being thus adapted for use at either side of the bed. 85

The fastening-plate 13 is simply a substantially-vertical plate to which the side rail 11 may be bolted and which is provided with 90 the laterally-projecting pins 17 and also with the wedge-surface 18, the latter inclining downwardly and outwardly from the post 10 and also laterally inward toward said post, so as to conform to the wedge-surfaces 15 of 95 the plate 12, with which it engages. The wedge-surface 18 of the plate 13 need not be continuous from its upper to its lower edge, but should engage one wedge-surface 15 of the plate 12 at its upper and lower portions 100 in order to attain the best results, and hence, as indicated by the dotted lines in Fig. 1, the middle portions of the wedge-surface 18 may be cut away or omitted and only a portion of the upper and lower ends of said surface be 105 permitted to contact with the wedge-surface

15. The fastening-plate 13 is connected with the fastening-plate 12 by simply guiding the pins 17 into engagement with the hooks 16 and by moving the wedge-surface 18 of said plate 13 downward into engagement with the wedge-surface 15 of said plate 12, the said wedge-surfaces closely binding the said plates 12 and 13 together and causing the pins 17 to maintain a firm engagement with the walls 10 of the hooks 16. The lateral inward inclination of the wedge-surfaces 15 and 18 is important, in that said surfaces interlock to prevent the fastening-plate 13 from having any lateral motion outward from the plate 12, 15 and thereby the fastening of the side rail to the end post is rendered rigid and secure and any lateral strain on the bed is effectually resisted by the firm surfaces 15 and relieved from the more delicate members represented 20 by the pins 17 and hooks 16. It will be observed that the plate 12, having the wedge-surfaces 15, is of the most durable character and capable of withstanding any usual strains which could properly come upon or against 25 the bed, and hence the bed possessing the fastening devices of the character hereinbefore described is entirely firm and durable and not at all likely to become impaired with any ordinary handling or use.

30 In the form of the fastening devices shown in Figs. 1, 2, and 3 the angle-iron side rail 11 will be bolted to the fastening-plate 13, and the transverse beam 19, connected with the spring-frame, (not shown,) will be secured by 35 a screw 20 to said plate 13 and also by a bolt 21 to said angle-iron side rail 11.

In the form of the invention shown in Fig. 4 the fastening-plate 13 is simply somewhat reduced in size from that presented in Fig. 1, 40 and to it is secured the angle-iron side rail 11, as usual. The form of bed indicated in Fig. 4 is intended for the class of spring-frames which simply rest upon the side rails instead of having the ends of their transverse beams 45 fastened by screws to both the fastening-plates 13 and side rails 11. The present invention is not confined to any special character of spring-frames, and hence is not limited to any special outline which may be given to 50 the fastening-plates 13 for their accommodation with any particular spring-frames.

I prefer that the fastening-plates 13 possess the two pins 17 and that the section 14 of the plate 12 possess the two hooks 16; but 55 I do not limit the invention to the use of any special number of the pins 17 or hooks 16, the essential consideration being that the plate 13 be interlocked with the section 14 of the plate 12 and that said plates have wedge-surfaces for engagement with one another, the wedge-surface on the plate 13 being at its outer edge and the wedge-surface on the plate 12 being at the base of the section 14. In the preferred form of the invention the said 65 wedge-surfaces will incline laterally and inwardly, as shown, or will be in some form rendering them capable of lateral engagement

with one another, so as to resist lateral strains and prevent the fastening-plate 13 from moving laterally from the plate 12, and this result may be accomplished whether the meeting surfaces 15 18 are flat, as shown, or correspondingly curved or given some other suitable outline.

What I claim as my invention, and desire 75 to secure by Letters Patent, is—

1. A bedstead - fastening comprising the plate 12 secured to the bed-post 10 and having the section 14 formed with the hooks 16, 16, one below the other, and said plate 12 having at the base of said section 14 the downwardly and outwardly and also laterally inclined wedge-surface 15, combined with the fastening-plate 13 having the laterally-projecting pins 17, 17, to engage said hooks, and 80 also having at its edge the wedge-surface 18 to engage said wedge-surface 15; substantially as and for the purposes set forth. 85

2. A bedstead-fastening comprising the two plates 12, 13, for connection with the post 90 and side rail respectively and provided with means for engaging the side of one plate with the side of the other plate, one of said plates being formed, independent of the said engaging or side locking means and in addition thereto, with the downwardly and outwardly inclined wedge and laterally-inclined locking-surface 15, and the other of said plates having the conforming surface 18 to be received by the said surface 15, whereby said plates in 95 addition to being interlocked one upon the other, are, by the said inclined surfaces 15, 18, firmly bound together and prevented from lateral displacement one from the other; substantially as and for the purposes set forth. 100

3. A bedstead - fastening comprising the plates 12 and 13, the former having the hook-like section 14, and the plate 13 having laterally-projecting means to engage said section 14, and said plate 12 having at the base 110 of said section 14 the downwardly and outwardly and laterally inclined wedge-surface 15, and said plate 13 having the corresponding surface 18 to engage said surface 15; substantially as and for the purposes set forth. 115

4. A bedstead - fastening comprising the plates 12 and 13, the former having the hook-like section 14 and at the base thereof and at the opposite sides of said section 14 the downwardly and outwardly and also laterally inclined wedge-surfaces 15, 15, and the plate 13 having laterally-projecting means to engage said section 14 and also having at its edge a wedge-surface 18 to engage one of the said side wedge-surfaces 15; substantially as 120 and for the purposes set forth. 125

Signed at Brooklyn, in the county of Kings and State of New York, this 27th day of November, A. D. 1899.

DAVID FRANK.
